UNITED STATES PATENT OFFICE.

BIRNEY C. BATCHELLER, OF PHILADELPHIA, PENNSYLVANIA.

PNEUMATIC TIME-LOCK FOR PNEUMATIC-TUBE SYSTEMS.

SPECIFICATION forming part of Letters Patent No. 707,071, dated August 19, 1902.

Application filed October 11, 1900. Serial No. 32,681. (No model.)

To all whom it may concern:

Be it known that I, BIRNEY C. BATCHELLER, a citizen of the United States of America, residing in the city and county of Philadelphia, 5 in the State of Pennsylvania, have invented a certain new and useful Improvement in Pneumatic Time-Locks for Pneumatic-Tube Systems, of which the following is a true and exact description, reference being had to the 10 accompanying drawings, which form a part thereof.

My invention relates to pneumatic-tube systems, and has for its object to provide for use with such systems a pneumatic time-escape- 15 ment for actuating a locking device, in turn regulating the movement of some movable part of the tube system.

The nature of my invention will be best understood as described in connection with the 20 drawings, in which I have illustrated my pneumatic time-escapement as adapted to regulate movements of a device by which carriers are delivered to the tubes and in which also I have shown several modifications of my de- 25 vice, all within the broad scope of my invention.

In the drawings, Figure 1 is a side elevation, partly in section, of a device for delivering carriers to the tube provided with my 30 pneumatic time-escapement. Fig. 2 is a sectional elevation of the time-escapement and lock. Fig. 3 is a sectional elevation of certain details of the apparatus shown in Fig. 1, not in themselves forming a part of my present invention. Figs. 4, 5, 6, and 7 are views 35 illustrating various modifications of my invention.

A, Fig. 1, is the pneumatic tube through which the carriers are transmitted. The upper part 40 of this tube (indicated at A') is formed with slots, through which it connects with a supply-pipe A³, communicating in turn with a source of air under pressure. (Not shown.)

A² indicates an offset from the portion A' 45 of the pipe, in which the finger P² is situated.

A⁴ is an annular casing through the bottom of which is formed a perforation registering with the top of the tube-section A'. Another 50 perforation A⁵ is formed through the casing A⁴ for the admission of the carrier, a holder a⁵ extending out from the bottom thereof.

A⁶ is an opening at the top of the casing directly opposite to the opening leading to the tube system, this opening being normally closed by a plug a⁶. 55

B is an annular casing fitting in the casing A⁴ and supporting the tube-section B', b b, &c., indicating spoke-like braces connecting the rim of the casing B with the tube-section. The casing and tube-section are provided, 60 preferably, with trunnion-like extensions, (indicated at B²), which are journaled on some fixed framework and to one of which, as shown, is attached the segmental gear, (indicated at B³ B⁴), indicating a pin attached to the pipe- 65 section B' and having connections, which are not shown because not needed in the present case.

C is a reciprocating rack moving on the slide indicated at A⁷ and connected through 70 a piston-rod C' with a piston C², moving in the cylinder D and having, as shown, a cushioning-cylinder C³ attached to it, which when the piston moves to the left, as shown in Fig. 1, is entered by the plunger, (indicated at C⁴). 75

D' and D² indicate ports leading to the opposite ends of the cylinder D, and D³ is a port leading, as shown, from the port D² to a pipe T.

E is a valve-chamber having in it the cy- 80 lindrical chamber E', at opposite ends of which are situated the ports E² and E³, connecting, through the portions e² and e³, with the ports D' and D².

E⁴ is the inlet-port for compressed air, and 85 E⁵ the exhaust-port.

F is a valve-rod having attached to it the piston-valves F' and F², which move in the cylindrical valve-chamber E', as shown.

F³ indicates the projecting end of the valve- 90 rod, and F⁴ the prolongation of the rod in the other direction, this portion of the rod being connected with the lever G and normally held in the position indicated in Fig.

1 by the action of the spring F⁵, having a 95 bearing against the pivot-head G⁴ and acting against a collar f⁵ on the valve-rod F⁴. The lever G is pivoted at G¹ and has connected with it the segment (indicated at G²) formed with a shoulder g² at its upper edge and the 100 slot G³, through which extends the stationary pin G⁵.

G^4 indicates a pivotal connection with the lever G , to which the portion F^4 of the valve-rod is directly connected.

H is a cylinder having arranged in it ports, 5 (indicated at H' and H^2), one leading through the front and the other into the side of the cylinder, as shown. (See Fig. 3.)

I is a piston moving in the cylinder H and having attached to it and projecting through 10 the front of the cylinder the locking-bolt I' , I^2 indicating a spring, which normally pushes the piston against the front face of the cylinder.

J and J' are pipe connections leading from 15 the ports H' and H^2 , the pipe J connecting with the chamber K^2 of the valve-casing K , which has formed in it the two chambers K' and K^2 , connected by a port K^3 , the chamber K^2 having, as shown, a head with a central cylindrical port K^4 formed in it, and the chamber K' being connected by a pipe K^5 with the source of air under pressure.

L is a valve normally seated on the port K^3 and having extending from its front face 25 the rod L' , which extends through the front wall of the chamber K' , while from the back face of the valve extends the hollow cylinder, (indicated at L^2), this cylinder fitting and moving in the cylindrical port K^4 and having 30 formed in it ports L^3 , which normally open into the chamber K^3 , but which are closed when the valve leaves its seat.

L^4 indicates a spring which holds the valve to its seat.

35 The pipe J' , leading from the port H^2 , connects with the upper end of a cylinder M , in the lower face of which is an opening M' . N is a piston moving in this cylinder and normally held in its upper position by a 40 spring N^3 . The rod N' extends down from the piston through the lower head of the cylinder and has attached to a yoke at its bottom the slide N^2 , which moves in the slot O^2 of the valve-lifting finger O , said finger having besides the slot a projection O' at one 45 end and an eccentric-ring O^3 at the other end, said eccentric-ring fitting on an eccentric P' , attached to a shaft P , to which shaft is also attached the finger P^2 , (shown in Fig. 50 1,) said finger being held in the position indicated by a spring.

In the parts above described the apparatus illustrated does not differ in general characteristics from similar apparatus shown and 55 described in former patents, with the exception of the provision of the port D^3 in a position where the movement of a valve alternately admits and cuts off the supply of air to said port.

60 Referring now to the portions of the apparatus shown which form the subject-matter of my present application, Q (see Figs. 1 and 2) is a bracket secured, as shown, to the end of the valve-chamber E and supporting 65 tubular portions Q' and Q^2 , arranged with an opening between their adjacent ends, as shown. The bracket has also formed on it

the extensions Q^3 , supporting a pivot q^3 , on which is pivoted the vibrating lock U , having at its free end its upper surfaces U' arranged so that in the lower position of the lock the end F^3 of the valve-rod will move over it, while from the lower face of the lock extends the finger U^2 , which when the lock moves up serves as a stop by coming in contact with the end of the valve-rod. The upper end of the tubular portion Q' has secured to or formed upon it the flared portion Q^4 , into which is connected the pipe T , as shown at q^4 , Q^5 indicating the stuffing-box plug, 80 screwed into the upper end of the tube Q' and affording passage for the rod S^2 .

Q^6 is a casting forming the upper portion of the diaphragm-chamber and having formed in it, as shown in Fig. 2, an opening Q^7 for the outlet of air and an opening Q^8 for the inlet of air. The outlet-passage Q^7 is closed by a valve R , held to its seat by a spring, as indicated, the action of the valve being to permit the ready escape of air from the diaphragm-chamber and to prevent the entrance of air through the same port.

S is the diaphragm, secured between the castings Q^4 and Q^6 and having secured to its center by means of the clamp-plates S' the rod S^2 , having a foot S^3 , which rests upon the upper part of the vibrating lock U , a spring S^4 acting to normally hold the diaphragm and rod S^2 in the position shown in Fig. 2.

S^5 is a plunger situated in the tubular portion Q^2 and held against the lower face of the lock U by a spring S^6 .

V is an air-inlet-regulating device having, as shown, a threaded end screwing into the opening Q^8 and formed with a perforation V' , 105 the opening of which is regulated by a needle V^2 , having a threaded spindle V^3 , turned by means of a handle V^4 .

To describe the operation of the special adaptation of the device shown in Figs. 1, 2, and 3 before referring to the modifications illustrated in Figs. 4 to 7, I would state that a carrier intended to be delivered into the pipe A is inserted in the rotatable tube B' , which in its receiving position lies as shown 110 in Fig. 1. The operator then moves the lever G toward the right, as shown in Fig. 1, thereby moving the segment G^2 downward until the notch g^2 comes opposite to the lock I' , which and the piston I is thrust forward by 115 the spring I^2 until the lock engages in the notch, locking the lever in position. If the valve-rod F^3 F^5 is free to move, it is moved by the movement of the lever shifting the valves F' and F^2 , so as to connect the port e^3 with 120 the port E^4 and the port e^2 with the exhaust-port E^5 , this movement of the valve-rod also thrusting the extension F^3 over the top of the vibrating lock U and preventing it from rising until the valve-rod has moved back to 125 normal position. If, however, the vibrating lock is in position to prevent the movement of the valve-rod when the lever G is moved, the lever simply compresses the spring F^5 ,

which as long as the lever is in locked position exercises its pressure against the valve-rod, so that as soon as the vibrating lock moves downward the valves are moved, as 5 above described. The admission of compressed air to the port E^3 and through said port and its connections to the front end of the cylinder D causes the piston C^2 to move backward, and said piston carrying the rack 10 C with it acts through said rack on the segment B^3 and through it on the rotatable pipe-section B' , turning it into vertical position, so that it registers with the upper end of the pipe-section A' , permitting the carrier to pass 15 downward through said pipe-section into the pipe A ; but the carrier in passing through the pipe-section A' presses against and depresses the finger P^2 , turning the shaft P and the eccentric P' , so that the end O' of the finger O 20 clears the end L' of the valve-rod, whereupon the finger O is at once drawn upward by the action of the spring N^3 acting on the piston N and through the piston-rod N' and its connection N^2 on the finger O ; but as soon as the 25 carrier passes the finger P^2 said finger resumes its normal position, as shown in Fig. 1, the shifting of the eccentric P' forcing the end O' of the finger O against the valve-rod L' and thrusting the valve L away from its seat and 30 its heel extension L^2 into the cylindrical bearing part K^4 , so as to close the openings L^3 . Air under pressure coming through the pipe K^5 passes then through the chamber K' , the port K^3 , and the chamber K^2 to the pipe J and 35 thence into the front end of the cylinder H , where, acting on the piston I , it forces said piston backward and retracts the locking-bolt I' , permitting the lever G to resume its normal position, as shown in Fig. 1. The piston 40 I in moving backward uncovers the port H^2 , which permits the compressed air to pass out of the cylinder through the pipe J' into the head of the cylinder M , where, acting on the piston N , it forces said piston downward until 45 the end O' of the finger O passes below the valve-rod extension L' , whereupon the spring L^4 at once closes the valve L , shutting off connection between the chambers K' and K^2 and opening the chamber K^2 to the exhaust-port 50 K^4 , so that the piston I can again move forward until the bolt I' comes in contact with the segment G^2 . When the air from the port E^4 is admitted to the ports $E^3 D^2$, it passes also through the port D^3 and the pipe T into the 55 lower portion of the diaphragm-chamber formed between the castings Q^4 and Q^6 , pressing the diaphragm upward, the air in the diaphragm-chamber escaping freely through the port Q^7 . The upward movement of the diaphragm of course carries with it the rod S^2 , which no longer presses against the upper face of the vibrating lock U , said lock being held in the position indicated in Fig. 2 by the extension of the valve-rod F^3 over its upper surface; 60 but as soon as said valve-rod is retracted the plunger S^5 , acting against its lower face, moves

the lock upward in front of the valve-rod F^3 , so that said valve-rod cannot again be moved forward until the rod S^2 resumes the position shown in Fig. 2. The rod is moved downward as soon as the pressure is relieved from below the diaphragm by the action of the spring S^4 ; but the motion of the rod is checked and regulated by the admission of air above the diaphragm, which is regulated by the 70 needle V^2 , so as to give any time interval required and so that the vibrating lock U will remain in position in front of the spindle F^3 for whatever time may be fixed as that within which no two carriers should be sent into the 75 tube.

My pneumatic time-lock may be used in connection with any of the movable parts of a pneumatic-tube system, and it may be modified in many of its details without departure 80 from my invention.

In Fig. 5 I have illustrated diagrammatically substantially the same pneumatic escape- 85 ment as is shown in Fig. 2, attaching to the lower end of the rod S^2 the finger S^5 , arranged 90 when the rod descends to act on the end X' of a pivoted lever X , W indicating the pivot, X^2 indicating the locking-face of the lever, and X^3 the stop-face, which when the lock is in position to engage the valve-rod F^3 rests 95 against the valve-rod, as shown.

In Fig. 4 I have diagrammatically shown a modified form of pneumatic time-lock in which the regulating device V is arranged so as to permit only a slow movement of the dia- 100 phragm and rod S^2 upward when air is admitted to the pipe T , an inwardly-opening valve R' being provided which when air is exhausted through pipe F permits the spring S^4 to return the diaphragm and rod to normal posi- 105 tion with great rapidity. In this construc- 110 tion I have shown the finger S^5 as arranged to act upon the end X' of the lever X at the end of its upward movement and with the effect of unlatching the face X^2 of the lever 115 from the end of the valve-rod F^3 .

In Fig. 6 the top of the diaphragm-cham- 120 ber opens freely to the air, as indicated at q^7 , and the pipe T communicates with the lower portion of the diaphragm-chamber through a 125 pipe-section T' , having in it a regulating- valve t' , the air after passing said valve en- 130 tering the chamber through pipe-section T^3 , and after the supply from the pipe T is cut off the lowest portion of the diaphragm-cham- 135 ber exhausts rapidly through the valve T^4 in the pipe-section T^2 . This device operates in practically the same way as that indicated in Fig. 4.

In Fig. 7 the construction is similar to that 140 in Fig. 6 in that the upper section of the diaphragm-chamber opens freely to the air; but in this construction the air passing to the diaphragm-chamber from the pipe T passes through the pipe-section T^2 and the 145 valve T^6 , situated therein, and exhausts from the diaphragm-chamber through the pipe-sec- 150

tion T' and the regulating-valve t', situated therein, the operation of this modification being the same as the device shown in Fig. 5.

Having now described my invention, what I claim as new, and desire to secure by Letters Patent, is—

1. In a pneumatic-tube system, a pneumatic cylinder and piston actuating a movable device forming part of the system, a lock for holding said movable device in one position, a pneumatic time-escapement device arranged to withdraw the said lock after the admission of compressed air to the escapement device, a source of air-supply having connections to the cylinder and escapement aforesaid and means for opening said connections to the source of supply or to exhaust.
2. In a pneumatic-tube system a pneumatic cylinder and piston actuating a movable device forming part of the system, in combination with a port leading to one end of the cylinder, a pneumatic time-escapement, a port leading thereto, a valve controlling the connection of said ports with a source of air under pressure and with an exhaust so that

air is admitted to and exhausted from one end of the cylinder and to and from the escapement during the same positions of the valve, and a locking device actuated by said time-escapement.

3. In a pneumatic-tube system a pneumatic cylinder and piston actuating a movable device forming part of the system, in combination with a port leading to one end of the cylinder, a pneumatic time-escapement, a port leading thereto, a valve controlling the connection of said ports with a source of air under pressure and with an exhaust so that air is admitted to and exhausted from one end of the cylinder and to and from the escapement during the same positions of the valve, and a locking device actuated by said time-escapement and arranged to engage and prevent a second movement of the valve to admit air to the port for a determined time.

BIRNEY C. BATCHELLER.
